UNITED STATES PATENT OFFICE.

SAMUEL WALD, OF NEW YORK, N. Y.

DETERGENT.

1,324,764.

Specification of Letters Patent.

Patented Dec. 9, 1919.

No Drawing.

Application filed May 6, 1919. Serial No. 295,063.

To all whom it may concern:

Be it known that I, SAMUEL WALD, a citizen of Hungary, but having declared my intention of becoming a citizen of the United States, and a resident of the city of New York, borough of Manhattan, in the county and State of New York, have invented a new and useful Detergent, of which the following is a full, clear, and exact description.

This invention relates to compositions of matter and has particular reference to detergents or cleansing agents and to the manner of compounding the same.

Among the objects of the invention is to provide a detergent calculated especially for the washing or cleansing of clothing, garments, or fabrics with the least amount of labor on the part of the housewife or laundress.

More specifically stated the invention has reference to the compounding of a detergent comprising several ingredients of a relatively strong character but the same being associated or mixed with other ingredients having the facility of so tempering or modifying the characteristics of said stronger agents as to render them safe in use but without detracting materially from their efficiency as dirt and grease destroyers.

With the foregoing and other objects in view the improved composition of matter herein set forth comprises a number of distinct ingredients and while I specify herein the specific ingredients and the several component proportions I wish to be understood that for some of the specified ingredients others having similar characteristics may be substituted under certain conditions without departing from the spirit of the invention.

The several ingredients and the proportions thereof that I have discovered by a long and careful series of experiments are as follows, by weight as in pounds:

45	Prussian blue-----	.10
	Soda peroxid-----	.90
	Soda ash-----	1.00
	Chlorid of lime-----	4.00
	Borax-----	4.00
50	Pulverized soap-----	5.00
	Potassium carbonate-----	5.00
	Ammonium carbonate-----	20.00
	Lye -----	60.00
		100.00

The small percentage of Prussian blue

serves the purpose similar to the use of laundry blue as ordinarily employed to neutralize the yellowish color that otherwise would be incident to clothing. The soda peroxid liberates oxygen forming hydrogen dioxid and adds to the efficiency of the compound as a bleaching agent. The soda ash serves among other things to preserve or maintain the integrity of the lye or potash granules and prevents slackening or efflorescence thereof. The chlorid of lime is a bleaching agent causing the liberation of nascent chlorin. The borax serves to soften the wash water, tempers or modifies the strength of the potash or its tendency to damage the fabrics, and also prevents the development of unpleasant or dangerous fumes. The soap is useful in the formation of suds and for acting upon certain characters of dirt or grease not reached by the other ingredients. The potassium carbonate, ammo or ammonium carbonate, and the like as well as the soda ash are all useful for dissolving the fatty deposits and dirts of various kinds.

In the assemblage of these several ingredients and the mixing thereof I take the ingredients severally and in the order in which they are indicated in the above tabulation mixing the first with the second and then the mixture with the third and so on, adding at each time the component having the next higher mass. By this method of mixing the components I observe the least possible danger of the formation of dangerous fumes or other results and also insure the most thorough intermingling of the several ingredients. All of the components employed are of a dry bulk or pulverulent nature and so the final composition is possessed of the same characteristics. After being mixed the composition is suitably packaged, labeled, and ready for the market and use. Directions accompany the same indicating the amount of the compound in a prescribed quantity of water. The cleansing is almost instant and requires no labor on the part of the laundress and the clothing or fabrics may be wrung out from the wash water and after being rinsed present a most satisfactory and pleasing appearance without danger of injuring the most delicate fabrics.

Instead of using this compound in the pulverulent form some of the users thereof prefer it in block or solid form which may easily be prepared by injecting into the mixture a small quantity of alcohol and sub-

jecting the composition to high pressure in molds or the like.

I claim:

1. The herein described washing composition comprising the following ingredients in pulverulent form thoroughly mixed together in the order and relative quantities stated:

10	Prussian blue	.10
	Soda peroxid	.90
	Soda ash	1.00
	Chlorid of lime	4.00
	Borax	4.00
15	Pulverized soap	5.00
	Potassium carbonate	5.00
	Ammonium carbonate	20.00
	Lye	60.00
		100.00

20 2. The herein described washing com-

pound comprising the following ingredients in pulverulent form thoroughly mixed together in the order and relative quantities stated:

25

Prussian blue	.10
Soda peroxid	.90
Soda ash	1.00
Chlorid of lime	4.00
Borax	4.00
Pulverized soap	5.00
Potassium carbonate	5.00
Ammonium carbonate	20.00
Lye	60.00
	100.00

30

35

a small quantity of alcohol being incorporated in the aforesaid pulverulent mixture and the same molded into cakes under pressure.

40

SAMUEL WALD.
